FITTING FOR ATTACHING SIDE RAILS TO
CORNER POSTS

John Ketola, Detroit, Mich.

Application October 15, 1942, Serial No. 462,072

9 Claims. (Cl. 5—295)

The invention relates generally to the connecting of structural members, and it has particular relation to improvements for connecting a bed post to a side rail or spacing member.

It is rather general practice in connecting a bed post to a side rail or spacing member to provide a pair of hooks, on the end of the side rail, which are adapted to project into long deep slots formed in the post and to engage pins embedded in the post and extending across the slots. The parts are so related that, upon inserting the hooks, downward pressure on the side rail such as by stepping on it brings the end of the latter towards the surface of the post. This is effected through a camming action between the hook and the pin, and considerable pressure is applied against the side of the pin especially if the hook wedges between the bottom of the slot and the pin. Because of this force, and also because of the deep, long slots, the wood is weakened and splitting of the post frequently occurs. Splitting of the side rail may occur also for similar reasons since usually the hooks are disposed in deep slots and are fastened to the rail by transverse pins.

Weaknesses in the structure may be lessened by increasing the size of the rail and post but this requires more wood and therefore is more expensive. Accordingly, it has been difficult in the prior structures in general use on wooden bed frames to provide an inexpensive connection between the post and side rail which would not at some time or other during assembly or use of the bed cause splitting of the wood at one or more corners of the frame. It may be added finally that the connections used heretofore in wooden frames have tended to be or to become loose during use and hence the frame would not remain rigid in shape.

One object of the present invention is to provide an improved means for connecting the bed post to a side rail, or the like, which will practically eliminate any danger of the wood splitting as a result of the connection.

Another object of the invention is to provide an improved connecting means which may be constructed of sheet metal in an efficient and economical manner.

Another object of the invention is to provide an improved connecting means for bed frames or the like which will largely avoid weakening of the parts through considerable cutting of the wood such as in the forming of deep, relatively long slots or grooves.

Another object of the invention is to provide an improved connecting means, such as men-

tioned, which still obtains the desirable result of drawing the end of the side rail into close proximity to the surface of the post.

Other objects of the invention will become apparent from the following specification, from the drawing relating thereto, and from the claims hereinafter set forth.

For a better understanding of the invention, reference may be had to the accompanying drawing, wherein:

Figure 1 is a side elevational view of a connection between a bed post and side rail, or the like, constructed according to one form of the invention;

Figure 2 is a view similar to Figure 1, but showing the two parts in separated relation;

Figure 3 is a detail view on a larger scale, showing the two connecting members which are fastened respectively to the side rail and bed post;

Figure 4 is a cross-sectional view on a larger scale taken substantially along the line 4—4 of Figure 1.

Referring to Figures 1 and 2, in particular, a corner bed post is indicated at 10 and a side rail or spacing member is indicated at 11. These parts may be constructed of wood, and it will be understood that four posts are provided and that the two opposing side rails 11 are connected at opposite ends to the post at the corresponding sides.

The connecting member or plate on the post, as perhaps best shown by Figure 3, comprises an angular sheet metal member 12 having leg elements 13 and 14. These legs are disposed in right angular relation and fit that corner of the post directed towards the center of the bed frame and preferably the leg 13 lays in a cut-out or rabbeted recess 15, not shown, so that the outer surface of the leg is substantially flush with the remaining surface of the wood at that side of the post. It is to be observed that this side of the post having the leg 13 thereon is adjacent to the end of the side rail 11, and this is the reason for preferably having the leg 13 flush with the surface of the post, as then it will not interfere with bringing the end face of the side rail against the post surface. One or more flatheaded screws 16 may be used to secure the leg 13 to the post.

Substantially intermediate its upper and lower ends, the leg 13 has a wedge-shaped projection 17 bent at right angles thereto, and this projection is disposed in a correspondingly shaped slot 18 formed in the post. An integral wall 20 of similar shape is reversely bent about the rear tapering edge of the projection 17, as indicated at 21,

and the projection and wall are disposed in laminated relation. In order to form a wedge-shaped sheath or pocket between the laminated parts, the projection 17 is laterally pressed out, as indicated at 22, and it is to be noted that the lower edges of the projection and wall are substantially together, as indicated at 23, so that the lower edge of the pocket is not open.

The leg element 14 of the member 12 has a reversely bent plate element 26 which extends substantially to the corner of the post, that is, substantially to the plane of the leg 13, and the element and leg 14 are secured in laminated relation and to the post by means of vertically spaced screws 27. In order to form vertically spaced sheaths or pockets between the elements 14 and 26, with the pockets on the order of that previously described, the metal in plate element 26 is outwardly pressed, as indicated at 28 and 29. It may be observed that the screws are so located that the elements are held in contacting relation at upper and lower sides of each pocket, so that the plate elements cannot spread apart adjacent the pockets. By having the pockets formed through outward pressing of the plate element 26, the leg element 14 may lie flat against the side of the post, and this increases the sturdiness or rigidity of the member, since both of the legs 13 and 14 are flat against the surfaces of the post and are held thereagainst.

The member 12 can be constructed from a single piece of sheet metal, and the pressed-out portions at the pockets may be formed readily therein before the legs are bent into final positions. After the pressing out operations and after the legs are bent into proper positions, the member may be readily applied to the post simply by moving the projection 17 into the slot 18 in the post until the leg 13 is against the post. Then the screws may be applied so as to positively anchor the member in position.

Now directing attention to the end of the side rail 11, a connecting plate member 35 is provided on the inner side thereof which includes a leg element 36 fastened to the side rail by means of vertically spaced screws 37. This leg element, at its lower end, has an inturned portion 38 resting against the lower face of the side rail and which is fastened thereto by means of a screw 39, shown by Figures 1 and 2. The projection 38 prevents undesirable load on the screws 37, since the load on the side rail, applied downwardly, can largely be taken through the projection 38 and lower side of the rail without requiring that it be exerted through the screws.

At that edge next to the post, the member 35 has a portion 40 bent outwardly at right angles and then again at right angles into parallel relation with the plate element, to provide a wedge-shaped blade or projection 41 disposed substantially parallel to the side surface of the rail. Immediately below the projection 41, the member has a portion 42 bent reversely to the portion 40, and which likewise terminates in a wedge-shaped projection or blade 43, disposed parallel to the projection 41. Due to the fact that the parts 40 and 42 are bent in opposite directions, the projections 41 and 43, while disposed in parallel relation, are separated transversely of the side rail. It may be added further that the projection 42 preferably is embedded in a rabbet or recess in the end face of the side rail, so that it will be flush with such end face.

Below the projection 42, a third portion on the member 35 terminates in a wedge-shaped blade

or projection 46 and these projections are like the projections 40 and 41, and are disposed in corresponding planes. It is to be observed and understood that the projections described may be formed from flat sheet metal integral with the leg 36, and that, in forming such projections, the metal is first cut along lines which divide them and that, after the cutting operation, the projections are bent in the manner described.

The wedge-shaped projections or blades on the member 35 are shaped and located so that they will cooperate with the three pockets or sheaths on the member 12. As seen best by Figures 1 and 2, the projections 41 and 46 are adapted to cooperate with the pockets 28 and 29, while, as best understood by Figures 3 and 4, the projection 43 is adapted to cooperate with the third pocket formed by the parts 17 and 20.

All of the projections or blades and the pockets or sheaths are so shaped that, upon downward movement of the rail 11 after the projections initially enter the pockets, the end face of the side rail is drawn closer to the post and finally, when the projections are substantially seated in the pockets, the end face of the side rail is brought against the post surface. The angularity of the projections and pockets is such that the side rail will not separate from the post except by upward lifting of the side rail and, consequently, when the connection is once made, there is no tendency for the side rail and post to separate. By having the vertically spaced pockets 28 and 29 and projections corresponding thereto, considerable rigidity is provided against any tilting of the post and side rail relatively in a vertical direction, although it should be understood, too, that the third pocket intermediate the first mentioned pockets also promotes this rigidity. Moreover, by having the pockets and projections spaced transversely of the side rail, considerable rigidity is provided against angling of the side rails and the posts in a horizontal plane, so that once the four corner posts and side rails are in position, a rather rigid rectangle is provided, assuming, of course, that the posts are connected by end members, as is ordinarily the case.

In so far as the member 12 is concerned, the face engagement between the leg 13 and the post surface will prevent any damage to the wood through forces applied in a direction perpendicular to the legs. Downward forces on the member 12 will be taken by the lower edge of the leg 13, the screws fastening both legs 13 and 14 to the post by the projection in the slot 18 and by friction between the legs 13 and 14 and the sides of the post.

From the foregoing description, it will be appreciated that a simple and economical connection may be provided for connecting bed posts to side rails or for connecting similar structural members, and that the connections may be made easily and without difficulty. Furthermore, it will be understood that danger of wood splitting, such as mentioned heretofore, is practically eliminated. In fact, the invention allows use of even smaller posts and side rails as compared to the prior practice, while still obtaining sufficient strength of structure since weaknesses such as mentioned are substantially avoided. In a bed structure, by having one of the connections at each corner, great rigidity is obtained, while still allowing easy assembly and disassembly of the parts. It may be observed, finally, that the two connecting members shown in the drawings are adaptable without change at the diagonally op-

posite corners of the bed frame, and that, at the corners of the frame, the connecting members may be changed in a manner readily apparent so as to obtain the same type of connection at each corner.

Due to the fact that the invention provides a connection which may be applied with very little cutting or weakening of the wood members with which it is used, it permits not only a reduction in size of wood members as compared with prior connectors for the same purpose but also permits the use of softer wood in such members than can be used with prior connectors.

Although only one form of the invention has been illustrated and described in detail, it will be apparent to those skilled in the art that various modifications may be made without departing from the scope of the appended claims.

What is claimed is:

1. A connection comprising an elongated sheet metal plate having integral sheaths on its opposite side edges which project from the same side of the plate in substantially parallel relation, and a second plate having portions at least one of which is bent to produce integral blades disposed in spaced relation and which project into the sheaths.

2. A connection comprising an elongated sheet metal plate having a pair of sheaths formed integrally with the plate and projecting angularly from one side edge thereof in spaced relation, a third sheath formed integrally with the plate and projecting angularly from the other side edge thereof with the third sheath disposed intermediate the pair of sheaths in a direction lengthwise of the plate, a second plate, and blades on one edge of the second plate and projecting into the sheaths respectively, said blades comprising portions integral with the second plate and bent away from the latter and then into substantially parallel relation thereto with alternating portions bent away from opposite sides of the plate.

3. A connection comprising an elongated sheet metal plate having a pair of sheaths formed integrally with the plate and projecting angularly from one side edge thereof in spaced relation, a third sheath formed integrally with the plate and projecting angularly from the other side edge thereof with the third sheath disposed intermediate the pair of sheaths in a direction lengthwise of the plate, a second plate, blades on one edge of the second plate and projecting into the sheaths respectively, said blades comprising portions integral with the second plate and bent away from the latter and then into substantially parallel relation thereto with alternating portions bent away from opposite sides of the plate, and an anchoring projection on one end of the second plate and comprising a portion integral with the plate and bent laterally therefrom.

4. In combination, a post or the like, a sheet metal member fastened to the post and having

leg elements projecting angularly from its opposite edges, plate elements laminated on and fastened to such leg elements respectively, means forming a sheath on each leg element comprising the leg element and the plate element fastened thereto, with one of the elements having a flat portion pressed out into spaced relation to the other element; a side rail or the like, and a connecting member on the rail having blades received in said sheaths.

5. In combination, a post or the like, a sheet metal member fastened to the post and having angularly related leg elements projecting from its edges, each of said leg elements having a portion reversely bent from one edge thereof so as to provide a laminated structure, means forming sheaths between the laminated parts and comprising such parts with a portion of one lamination spaced from the other; a side rail or the like, a plate fastened to the rail, and blades on the plate and respectively received in the sheaths.

6. A connecting member comprising a sheet metal plate having integral leg elements projecting angularly from opposite edges thereof in substantially parallel relation, each of said leg elements having a reversely bent portion to provide laminated parts, and means forming a sheath between each pair of laminated parts and comprising such parts with a portion of one part pressed out into spaced relation to the other.

7. A connecting member comprising a sheet metal plate having portions along one edge which are respectively bent transversely to the plate and in opposite directions, and blades on the ends of such portions which are disposed in substantially parallel relation to each other and substantially parallel to the plate but at opposite sides of the latter.

8. A connecting member comprising an elongated sheet metal plate having portions along one of its longer edges which are respectively bent transversely to the plate and in opposite directions, blades on the ends of such portions which are disposed in substantially parallel relation and substantially parallel to the plate but at opposite sides of the latter, and a projection on one end of the plate and comprising an end portion of the latter bent away from the plane of the plate.

9. In combination, a frame member or the like, a sheet metal plate fastened to the member and having a leg element projecting angularly from one edge thereof, said leg element having a portion reversely bent from one edge thereof so as to provide a laminated leg structure, means forming a sheath between the laminated parts and comprising such parts with a portion of one part pressed out into spaced relation to the other, a second frame member, a plate fastened to the second frame member, and a blade on the plate and projecting into the sheath.

JOHN KETOLA.
